York, N.Y., a corporation of New YorkFiled Apr. 16, 1954, Ser. No. 423,815
5 Claims. (Cl. 235—173)

This invention relates to apparatus employing electron valve means such as trigger circuits, and more specifically to electronic accumulators, and has for its object operating such devices whereby the component trigger circuits are operated relatively continuously. The principle of the invention may, however, be adapted to other types of apparatus using electron valve means.

According to the method of operation here disclosed, the accumulator orders, which are capable of remaining in stable states, operate continuously in the absence of differential value entries and have their operation interrupted only upon entry of such values.

The registers, widely employed in electronic accounting and computing machines for purposes such as storage and the algebraic summation of values, usually comprise trigger circuits based on the cross coupling of vacuum tubes. When one tube conducts the other is shut off. The frequency of reversal in the conduction status of the two tubes is directly related to the amount of use required of the register. Such use varies all the way from the substantially continuous to a very infrequent operation.

Experience with registers in the latter type of service indicates that operation of the trigger circuits may be erratic. More specifically, the tubes which are in shut-off condition for long periods of time do not respond to triggering pulses.

The location of such tube failure is believed to be its cathode and the cause is the formation of a high internal resistance, termed "interface resistance." Briefly, over a period of time, when a tube is cut off and the anode-cathode current is little or nil, an insulating compound forms between the oxide and its supporting core. This results in reduced current flow when conduction is required. Where the duty cycle of a vacuum tube is high the value of the interface resistance is maintained low.

Registers for differential values may also be constructed of semiconductors such as crystal diodes and transistors either alone or in combination with vacuum tubes. Where registers are comprised of trigger circuits employing semiconductors alone it has been found that adjustment must be made to start the device, that adjustments must be made during their operation, and that there is a minimum keying pulse repetition rate.

The cause of such difficulty is attributable to an inherent characteristic of presently available semiconductor materials such as germanium and silicon wherein variations in temperature of the material affect electrical characteristics. The temperature variations are largely induced by and dependent upon the conduction status of the semiconductor employed as a diode or as a transistor.

A high duty cycle for register triggers, comprising transistors alone or transistor-tube combinations, has beneficial effects. In the case of an all-transistor trigger a relatively constant operating temperature level is main-

2

tained. Thus, electrical characteristics are relatively constant and circuit tolerances are broadened. In the case of the transistor-tube trigger two results are achieved. The effect of the tube's interface resistance is maintained low. Further, any residual effects of temperature variations on the transistor, not previously compensated for by the tube, are reduced if not eliminated.

In the accompanying drawings FIGS. 1A and 1B are a circuit diagram of the instrumentalities employed and 10 their connecting circuits, and FIG. 2 is a time chart showing the sequence of operations during two complete cycles.

The machine has a standard keyboard with a column of keys representing the ten digits from each order. 15 Each key that is depressed closes a circuit which remains closed throughout the entry cycle. The entry cycle is initiated by depressing a "motor bar" on the keyboard, and at the conclusion of the entry cycle the keys and motor bar are released, re-setting the keyboard for the 20 next entry cycle.

In addition to the keys, each order of the keyboard has a control pentode designated in the diagram FIG. 1A, V16U, V16T, V16H and V16TH for the units, tens, hundreds and thousands orders respectively. The associated resistors are marked R40U, R40T, R40H, and R40TH, respectively. Each of the nine digits has a resistor marked DR¹ to DR⁹ respectively. The resistors DR¹ are connected to the "1" keys in all four orders of the keyboard, the resistors DR² to all the "2" keys, and 30 so on, so that on depressing a key in the keyboard a circuit is made with the order selecting pentode and also with the appropriate resistor. A standard multivibrator oscillator, as designated in FIG. 1A, is employed for producing timing and controlling impulses.

35 Certain of these pulses are employed to drive a five-section commutator continuously. The sections of the commutator are designated CO-5, C 9-4, C 8-3, C 7-2, and C 6-1, respectively, and the resistors DR¹ etc. are 40 so connected to the commutator as to interrupt the entry into the accumulator of that number of impulses which is the complement of the digit represented by the depressed key. Two complete cycles of operation of this commutator delimit a complete entry cycle. The first 45 ten index points are employed to effect the entry of the amount entered upon the keyboard, by interrupting the entry of the appropriate number of impulses into the accumulator through the entry triggers, one for each order marked EU, ET, EH, and ET^H in FIG. 1B for the units, tens, hundreds, and thousands orders respectively of the 50 accumulator. These triggers are normally "on" and continuously transmit to the several orders of the accumulator ten impulses for each complete entry of twenty index points except when an amount to be entered is set 55 up on the keyboard and the motor bar is depressed. The units, tens and hundreds have "carry circuits" marked Cu, Ct and Ch in FIG. 1B, but these circuits are "off" except when the motor bar is depressed and hence the successive entry of ten impulses during the cycles occurring between entries through the keyboard resets the accumulator orders at the same digital value at the end of 60 each such cycle.

The second portion of the entry cycle, comprising ten index points, is employed for carry effecting purposes, 65 which take place only during those cycles when a number

set up on the keyboard is entered by depressing the motor bar.

This motor bar causes a single entry control device, so marked in FIG. 1A and comprising two triggers T^1 and T^2 , to function in a manner such that one entry cycle of twenty index points follows in correct timed relationship with the commutator. The machine also has a "reset" device, so marked in FIG. 1A and a supplemental commutator C 10. The function of these devices will be later described.

In the drawings the elements such as tubes, resistors, condensers, etc. are indicated by the conventional symbols for such elements, and reference characters are applied to such of these elements as are referred to in the following description. The make-up of the several instrumentalities will not be specifically described, but will be clearly apparent from the drawings and the description of the operation of the machine. Reference will also be made to the time chart FIG. 2 which shows the status of the various instrumentalities at the successive index points in the complete entry cycles of the numbers 0 5 9 3 and 0 4 0 5 used as specific examples in the description which follows.

From power supplies, not shown, suitable potentials are applied to lines 2, 4, 6, 8 and 10, and to the heaters of various vacuum tubes. The wiring of the heaters is not included.

The oscillator includes tubes V2 and V4 and operates in the usual manner to provide square wave impulses. The impulses produced on R2 are differentiated and applied to the grid of V6. Since the grid bias of V6 is normally zero only the falling front of a pulse derived from R2 effects V6. The negative pulse produced by such falling front causes V6 to shut off and positive pulses to be continually produced on wire 20. The square wave pulses produced on R4 are differentiated and applied to the grid of V8. The grid bias of this tube is also zero and, accordingly, negative pulses only are effective and cause V8 to shut off. The resulting positive pulses are applied through wire 22 to tubes V12 of triggers EU and ET for the units and tens orders and through tubes V14 of the triggers EH and ETH of the hundreds and thousands orders.

The pulses on wire 20 are employed to operate the five-stage commutator. The 0-5 stage is shown in FIG. 1 and the other stages indicated by box diagrams. Since the impulses on wire 20 are produced continuously, such commutator likewise functions continuously. The timing diagram (FIG. 2) shows the pattern of wave forms produced as the various stages in the commutator (FIG. 1A) function sequentially. It should be mentioned that this commutator automatically adjusts itself to the proper sequential pattern of operation irrespective of the "on" and "off" status of the component stages when the power is turned "on." A supplementary commutator stage C-10 is provided. The impulses for driving C-10 are derived from R-8 of the C 0-5 stage of the commutator and are applied thereto via wire 26.

Whenever the potential drop across R-8 increases, a negative pulse is produced on wire 26 and this pulse is effective to switch C-10 either "on" or "off." Since a negative pulse is produced on wire 26 once every ten index point positions, C-10 is alternately "on" and "off" for ten index point positions. One complete operation of C-10 delimits one complete entry cycle.

The negative pulse on wire 26 is applied twice each cycle to junction 60 in entry triggers E_u and E_t for the "units" and "tens" orders respectively. The effect of such impulse is to turn E_u and E_t on. The R6, R28 junction of commutator stage C 0-5 is coupled to wire 28 by condenser C2 and wire 28 returns to line 10 through resistor R30 of entry trigger Eth of the "thousands" order. Wire 28 also connects to the grids of tubes V10 included in entry triggers E_h of the "hundreds" order and E_{th} . Normally, the grid bias of all tubes V10 is highly negative

and, accordingly, the respective tubes V10 are shut off. It is understood, therefore, that a negative pulse on wire 28 has no effect on a tube V10. When the R6, R28 junction of commutator stage C 0-5 rises in potential, the resulting pulse on wire 28 is effective to cause the tubes V10 to conduct, thus switching triggers E_h and E_{th} to "on" status.

With the entry triggers on, the control grid bias of tubes V12 of triggers E_u and E_t and tubes V14 of triggers E_h and E_{th} is zero. The impulses on wire 22 cause anode current to flow in the tubes V12 and negative pulses to be produced on resistors R32 of triggers E_u and E_t . These negative pulses are effective to continuously impulsive the units and tens orders of the accumulator. The impulses on wire 24 are effective to cause anode current to flow in the tubes V14. The resulting negative pulses on resistors R32 of triggers E_h and E_{th} are effective to continuously impulsive the hundreds and thousands accumulator orders.

In starting up the machine, when there is application of power to the various lines and to the heaters, the pattern of "on" and "off" status established by the accumulator triggers is largely a matter of chance, and the phase relationship may differ not only between the accumulator orders themselves, but also between the accumulator orders and the commutator. Provision must be made, therefore, to establish the correct phase relationship not only between all orders of the accumulator but also between such orders and the commutator prior to effecting entries. The detailed manner in which this resetting operation is carried out is described subsequently. It is sufficient to here state that the result of a resetting operation is to establish the "on" and "off" pattern of the accumulator triggers such that all orders pass from "0" to "1" in response to the keying pulse just following the reset pulse.

After the reset is effected the entry of the first number 0593 is made. The first step is to depress the "0," "5," "9," and "3" keys in the thousands, hundreds, tens and units orders, respectively, of the keyboard. Such operation causes closure of contacts 0TH, 5H, 9T and 3U. The closed 0TH contact maintains the suppressor grid of V16TH at the potential of line 6. The closure of keyboard contacts 5H, 9T and 3U connect the suppressor grids of V16H, V16T and V16U to resistors DR5, DR9 and DR3, respectively. Even though such connections are established, the pulses applied to the suppressor grids of the three V16 tubes has no effect on the anode current flow at this time inasmuch as their control grids are highly negatively biased.

Initiation of the actual entry is effected by manual manipulation of the motor bar ST. Condenser C4 is charged to a potential equal to that developed across R34. Operation of the motor bar reverses the position of the contacts ST allowing the condenser C4 to discharge across R36. The resulting positive pulse causes V18 to conduct momentarily, thus shifting T1 in the single entry control device to "on" status. This manually initiated operation can occur at any time with respect to a complete cycle of operation of the commutator.

With T1 in "on" status, the screen grid voltage of V20 is at a raised potential. The control grid of V20 connects to R38 which receives a positive impulse when supplementary commutator C-10 goes on. Accordingly, at the time when such action occurs, the positive pulse received by the V20 control grid, in combination with the raised screen potential, causes V20 to conduct momentarily thus shifting time delay trigger T2 from "off" to "on" status. Such action is shown occurring in the timing diagram (FIG. 2). It should be mentioned that the shifting of C-10 from "off" to "on" status denotes the beginning of a complete entry cycle. With T2 on, its point 62 is substantially at the potential of line 4 thereby reducing the control grid bias for tubes V16H, V16T and V16U to substantially zero. The control grid bias of V16TH also is reduced to zero, but to no effect.

It has been previously mentioned that all orders of the accumulator are continually impaled except when entries and carries are to be effected. It has also been previously mentioned that an entry of a chosen digit is effected by interrupting the continuous operation of the order in which said digit is to be entered for a period of time proportional to the true complement of such digit. Upon entry of -0593- the continuous operation of the units order is interrupted for seven index points, the tens order is interrupted for a single index point, and the hundreds order is interrupted for five index points. Prior to effecting entry, it is assumed that the accumulator is established in -0000- status, that is, is reset. When such condition obtains, all orders of the accumulator stand at -9999- at "D" (beginning of a cycle) and at one-half index point after "D" are impaled and all advance to -0000-. This is clearly seen by reference to the timing diagram (FIG. 2).

The closure of keyboard contacts 3U (FIG. 1A) connects DR3 with the suppressor grid of V16U. Accordingly at "7" in the entry cycle, the pulse applied to the suppressor grid of V16U causes it to conduct and a negative pulse is produced on R40U. The R40U, V16U junction is coupled to the entry trigger E_u at condenser C6. Thus, the negative pulse on R40U is effective to switch E_u off. Such action is shown occurring at "7" in FIG. 2. With E_u (FIG. 1B) off, V12 is rendered non-conductive and the keying pulses supplied to the V12 suppressor grid from wire 22 are no longer effective to impale the units order triggers. The interruption brought about by this action is shown in FIG. 2. The closure of contacts 9T (FIG. 1A) in the tens order couples the suppressor grid of V16T to DR9. The pulse on DR9 at "1" causes V16T to momentarily conduct and the negative pulse produced on R40T shuts off E_t at this time.

The impulse appearing on DR5 (FIG. 1A) at the "5" time in the cycle is effective through the now closed keyboard contacts 5H to reduce the suppressor grid bias of V16H. The resulting negative pulse appearing on R40H is applied to the E_h gate trigger turning it off. With this trigger off, further impaling of the hundreds order is interrupted commencing at the "5" time in the cycle. See FIG. 2.

Inasmuch as no entry is to be effected into the thousands order, E_{th} remains on throughout the entry portion of the cycle and the thousands order is continually impaled as shown in FIG. 2.

At the termination of the entry portion of a cycle, the commutator trigger C 0-5 (FIG. 1A) switches on and the negative pulse developed on wire 26 switches the triggers E_u and E_t on status. The positive pulse on wire 28 causes E_h to turn on. Accordingly, at one-half an index point following such action, impaling of the first three orders of the accumulator is resumed. It is seen from the timing diagram, FIG. 2, that at such one-half index point following "0," the units order stands at -3-, the tens order at -9-, the hundreds order stands at -5- and the thousands order stands at -0-.

The first three orders of the accumulator are provided with carry circuits which includes carry triggers designed C_u , C_t and C_h , FIG. 1B. The detailed mode of operation of these triggers during the entry portion of a complete cycle will be later described. It is sufficient to here state that, if any carry trigger is in off status at the "11" time in a cycle, no carry is applied to the next higher order. Reference to FIG. 2 indicates that the carry triggers are off at the time specified. This is to be expected since the addition was of the amount -0593- to -0000-.

The single entry control device is reset at the conclusion of an entry cycle to receive the next entry. When the commutator trigger C 6-1 operates at "1" in a cycle, a positive pulse is produced on R42, to which is connected the control grid of V22. Since T2 is on, the

screen grid of V22 is at raised potential. Accordingly, the positive pulse produced on R42 renders V22 conductive, thus switching T1 off. Subsequently at "0" when CO-5 operates, a positive pulse is produced on R44 to which is connected the control grid of V24. The screen grid of V24 is now at high potential, since T1 is off. Thus, the aforementioned positive pulse on R44 causes V24 to momentarily conduct thereby switching T2 off. With T2 off, its junction 62 drops in potential sufficiently to maintain any of the tube V16 non-conductive even though digit representing pulses continue thereafter to be applied to the V16 suppressor grids. At the conclusion of the entry cycle the keys and motor bar are released in the usual manner by mechanism not 15 shown.

On entering the second number -4008- on the keyboard, the 0TH, 4H, 0T and 8U contacts are closed. Manipulation of motor bar ST to a reverse position from that shown initiates a second complete cycle of 20 twenty index point positions. During the entry portion of this cycle, the units and hundreds order entry triggers E_u and E_h turn off at "2" and "6," respectively. Accordingly, continuous operation of the units order and the hundreds order are respectively interrupted for two 25 index point positions and six index point positions.

The addition of -8- to -3- in the units position requires that a carry be determined and applied to the tens order. Since the tens order stands at -9-, following the first entry and has -0- added thereto, during the 30 second entry the application of the carry increment from the units order requires that the tens order pass this carry along to the hundreds order. Since the hundreds order stands at -5- following the first entry and receives a -4- during the second entry, the application thereto 35 of the carry from the tens order requires that it pass a carry along to the thousands order. The manner in which carries are determined and effected will now be described in detail.

As each order of the accumulator is continuously 40 impaled, it is manifest that each order passes from -9- to -0- sometime between "D" and "0" (FIG. 2) when no entry is applied thereto. If a carry were effected at each cycle of impulses a "1" would be added to each order except the units order at each cycle, and hence 45 there must be no "carry" unless the order receives an entry. A carry, however, is required whenever an order reaches -9- after "D" and before "0" and such order receives an entry. Provision is made, therefore, for determining when an order reaches -9- in the interval 50 specified and further for determining the presence of an entry. Such is accomplished in the following manner.

A carry trigger is provided in conjunction with the three lower orders. These carry triggers are impaled on at "D" every cycle. Upon any order reaching -9- prior 55 to "0," the associated carry trigger is switched off. If there is an entry, the carry trigger is switched on. Thus, the presence of the two conditions in a "D" to "0" interval causes the carry trigger to be on at the beginning of the carry portion of the cycle. Manifestly, if there is 60 no entry the carry trigger is off following "0." A carry is effected into a higher order when a carry trigger is on following "0."

The pattern of operation of any order containing a -9- is such that at "11," (FIG. 2) the stages of such 65 orders manifest the -9-. This condition is employed to effect carries through orders which stand at -9- and receives carries from lower orders.

The entry of -0593- with all the orders standing at "0" is an example of an entry requiring no carry. At the 70 beginning of any complete twenty-point cycle, the carry triggers C_u , C_t and C_h are turned on. At such "D" time, commutator trigger C-10 switches on and the positive pulse on R38 renders tube V26 conductive. A negative pulse is produced on resistors R48 and R50, and wires 75 32 and 34, respectively. The negative pulse on wire 32 is

effective to switch C_u and C_t on and the negative pulse on wire 34 causes C_h to switch on. With T2 on, its junction 62 is substantially at the potential of line 4 and the control grid bias of tubes V28 in the carry triggers is zero. When the units order gate trigger E_u switches off at "7," a positive pulse is developed at its junction 64. This pulse is applied to the suppressor grid of V28 associated with C_u , rendering V28 momentarily conductive. The negative pulse developed on R48 causes C_u to switch off. No further actuation of C_u occurs during the entry portion of the cycle (see FIG. 2) since the units order does not reach -9- prior to "0."

Referring now to the tens order (FIG. 1B), the gate trigger E_t switches off at "1" and the positive pulse produced by the rise in potential of its point 64 causes V28 related to C_t to conduct, thereby switching C_t off. No further actuation of C_t occurs during the entry portion of the cycle (see FIG. 2), since the tens order does not reach -9- prior to "0."

With T2 (FIG. 1A) on, as explained previously, there is an increased potential drop across its resistor R72. Wire 42 connects from a point on R72 to the grid of V45. The raised potential drop across R72 causes V45 to become more conductive, increasing the potential drop across R74. This potential rise across R74 is effective to prime tubes V30 and V48 without causing them to conduct. When gate trigger E_h switches off at "5" in the cycle, the resulting decreased current flow through R50 causes a positive pulse to be applied to the grid of V30. Since V30 is primed, the pulse applied to V30 causes it to conduct and the negative pulse produced on R52 causes C_h to switch "off." As is true in the case of C_u and C_t , no further actuation of C_h occurs during the remaining portion of the entry cycle and, accordingly, all carry triggers are off at "11" in the succeeding half of the complete cycle. With these carry triggers all in off status, no carries are applied to any of the various orders.

At the beginning of this second entry cycle, the switching of C-10 causes V26 to conduct and negative pulses to appear on wires 32 and 34. As previously described, these pulses cause the switching on of all carry triggers. With T2 on, the control grids of tubes V28 and V32 are at zero bias and V45 is more conductive, thus priming V30 and V48.

Reference to FIG. 2 indicates that the units order reaches -9- at one-half after "4." The grid of V34 (FIG. 1B) connects to junction 60 (ST8) and the grid of V36 connects to the junction 60 (ST1). As the units order reaches -9-, both tubes V34 and V36 are shut off and current flow through R54 decreases. The resulting positive pulse is applied to R56 which renders V32 conductive. The negative pulse developed on R148 is applied to C_u , switching this trigger off. At "2" in this cycle when E_u switches off, the positive pulse derived from junction 64 (E_u) is applied to the suppressor of V28 and again causes a negative pulse to appear on R148 thereby returning C_u to on status. See FIG. 2.

In connection with the tens order, the trigger circuits reach -9- at one-half after "D." Accordingly, V34 and V36 (FIG. 1B) in this order are both shut off at this time and the positive pulse on R54 is applied to R56 rendering V32 conductive. The negative pulse on R48 switches C_t off. Since there is no entry of a digit into this order, E_t remains in on status until the end of the cycle and, accordingly, C_t remains off.

The entry of -4- into the hundreds order causes the E_h gate trigger to switch off at "6." The positive pulse on R50 at such time renders V30 conductive and the negative pulse on R52 causes C_h to switch off. Since the hundreds order does not reach -9- prior to "0," C_h remains off. In the entry cycle in which -0408- is added to -0593-, it is seen by reference to FIG. 2 that the units order carry trigger C_u is on and that the remaining carry triggers C_t and C_h are off at the beginning of the second portion. It may be further observed that at one-half after "0" both the tens and hundreds orders stand at -9-. Under these

conditions it is seen therefore that the carry which is applied to the tens order must likewise be applied to the hundreds and thousands order.

Such carry operations are initiated at "11." Since C_u is on, the control grid bias of V12 (C_u) is zero. Reference to FIG. 2 indicates that C-10 is off at "11." Accordingly, the control grid bias of V38 (FIG. 1A) is now zero. The operation of the commutator during the second portion of a cycle causes a positive pulse to appear on DR1 at "11." This pulse is applied to the suppressor grid of V38. The momentary conduction of V38 causes a negative pulse to appear on R58 and this negative pulse is applied via wire 36 to R60. The grid of V40 connects to R60, and it is seen that V40 is normally zero biased. The negative pulse so applied to V40 shuts it off momentarily and a positive pulse appears on R62. This positive pulse, in turn, is applied to the suppressor grid of V12, C_u , and causes anode current to flow not only through V12 but also R40T. The result of this action is to cause gate trigger E_t to switch off at "11." See FIG. 2.

The negative pulse on R40T is simultaneously applied to R60 and the grid of V40 in the tens order. The resulting positive pulse on R62 in this order is applied to the suppressor grid of V42. The control grid of V42 connects to resistor R64. Since the tens order stands at -9- at the "11" time, both V34 and V36 in this order are non-conductive and there is a high potential drop across R64, thus reducing the control grid bias of V42 to zero. The pulse on R62, therefore, causes V42 to conduct and a negative pulse to appear on plate load resistor R40H common to tubes V42, V48 and V16H. This pulse causes the E_h trigger to switch off at "11."

The negative pulse on R40H is also applied to the grid of V40 in the hundreds order. A positive pulse is produced on R62 and applied to the suppressor grid of V42. Reference to FIG. 2 indicates that at "11" the hundreds order stands at -9-. Accordingly, ST1 and ST8 (FIG. 1) are "on" in the hundreds order and transistors TR2 and TR4 are concurrently conductive.

The collector circuits of TR2 and TR4 return to line 10 via R76 and R78, respectively. With these transistors conductive there is a large potential drop across both R76 and R78. Thus, the control grid and suppressor grid bias of V50 is substantially zero and the potential drop across R80 is low and V52 is shut off. Since this is the case, there is a large potential drop across R64 to which is connected the control grid of V42. The pulse on R62 causes V42, therefore, to momentarily conduct and a negative pulse to be produced on R40TH. This pulse is applied to the E_{th} trigger turning it off.

Thus, at "11" in the carry portion of this entry cycle in which -0408- is added to -0593- impulsing of the tens, hundreds and thousands orders of the accumulator ceases. This action continues until the switching of CO-5 turns the E_t , E_h and E_{th} gate triggers on at "D." The result of interrupting impulsing of these three orders for nine index point positions is an application of a carry to each of three orders simultaneously. Reference to FIG. 2 indicates that at one-half after "D" the status of the triggers in the four orders manifests the summation amount -1001-.

Resetting

As previously mentioned, provision is made for resetting the electronic accumulator to -0000-. Such action occurs on a timed basis and is manually initiated. The effect of such operation is to instantaneously turn off any of the accumulator triggers which may be on. The operation is carried out without interruption of the continual impulsing of the accumulator orders and, accordingly, resetting occurs at a time which is displaced from normal impulsing time by one-half an index point position. In order that the accumulator orders (FIG. 1) represent -0000- with respect to a complete commutator cycle, it is required that the first of the continual impulses be received by such zeroed orders at either one-half after

"9" in a cycle, or one-half after "11" in a cycle. That is to say, it is required that reset to -0000- be effected either at "9" or at "11" in order that the accumulator advance to -1111- on the next continual impulse. The "11" time was arbitrarily chosen as the reset time.

The positive pulse continually produced on R62 at "11" is applied to the suppressor grid of V44. With reset switch SR open, the control grid bias of V44 is highly negative. The closure of SR initiates a reset by reducing the control grid bias of V44 to zero. The next positive pulse at "11" received by the suppressor grid of V44 renders it conductive and a negative pulse appears on R66. This negative pulse is applied to the grid of normally zero-biased tube V46, causing it to shut "off." A positive pulse appears on R68 and wire 38. This wire extends to all triggers in the units and tens orders of the accumulator via diodes D2. The shut "off" of tube V46 causes the potential of wire 38 to rise from considerably below that of line 4 to considerably above. In this manner all triggers in these two orders including the carry triggers are shut off. The negative pulse on R66 is also applied to R70 and wire 40. Wire 40 extends to all triggers of the tens and hundreds orders via diodes D4. Normally the potential of wire 40 is substantially that of line 4. The negative pulse on R70 also carries the potential of wire 40 considerably below that of line 4 thus instantaneously shutting off the trigger circuits in the hundreds and thousands orders including the carry triggers.

A resetting operation is shown occurring in the right-hand portion of FIG. 2 and it is seen that it occurs at a time which does not interfere with the continual impulsion of all orders. Furthermore, all orders advance from -0000- to -1111- at one-half after "11" as fundamentally required.

In this embodiment of my invention each complete cycle restores the register orders to the condition existing at the beginning of the cycle so that there is no change in the totals accumulated. That is to say, a total print operation at the conclusion of any cycle, assuming no additional entries were made, would be the same notwithstanding the continuous impulsion of the register orders. In the apparatus illustrated the entry circuits are so modified that the digits registered on the keyboard are not added to the respective orders by transmitting the indicated number of impulses to such orders as in the customary operation, but by interrupting the continuous transmission of impulses to an extent corresponding to the complement of the digits entered on the keyboard, and the carry circuits are modified so as to correctly carry forward to the next order the required added impulses only in the cycle of operations where an entry is made on the keyboard.

It will be understood, however, that the disclosed apparatus for continuously impulsing the register orders may be modified. For example, the carry circuits can be allowed to function during the cycle when no entry is made on the keyboard by providing means for adding "1" to the digits order for each cycle. By such procedure 10,000 would in effect be added to the four register orders for each cycle of operation thereby restoring the units, tens, hundreds and thousands orders to the same condition at the conclusion of each cycle.

The apparatus might also be so modified as to interrupt the continuous impulsion of all the registered orders upon an entry being made on the keyboard and restoring the continuous impulsion at the conclusion of the cycle in which the entry is made.

It is to be understood, therefore, that my invention is not limited to the specific apparatus disclosed in the specification and drawings, but covers all such modifications hereof as fall within the scope of the appended claims.

The term "registers" is used in the appended claims in a broad sense to include electronic apparatus contain-

ing a plurality of interconnected circuits capable of operating through successive complete cycles with the circuit restored at the end of the cycle to its initial condition, and not in a narrow sense to imply any particular interconnection or any particular use to which the apparatus is put.

I claim:

1. In an electronic register in which information is accumulated and stored in an electronic accumulator capable of remaining in stable states and in which said stored information normally utilizes only a part of said electronic accumulator, the improvement which includes means for generating information to cycle the electronic accumulator through a whole number of cycles, means to transmit said generating cyclic information to said electronic accumulator, and means to intermittently interrupt said transmission to apply information to be accumulated and stored to said accumulator.
2. In an electronic register having a cyclic information accumulator including a plurality of binary stages, the electronic circuitry for each stage including at least two electronic valve elements which are alternately rendered "on" or "off" as information is applied and in which accumulated information is represented by the pattern 25 of "on" and "off" statuses of said electronic valve elements, the improvement which comprises means to generate information to cycle said accumulator through a whole number of cycles during each cycle of which each of said electronic valve elements is rendered conductive, 30 means to transmit said generated information to said accumulator, and means to intermittently interrupt said transmission to apply information to be accumulated to said accumulator.
3. An electronic register having a plurality of ascending 35 orders, the electronic circuitry for each order including a plurality of electronic valve elements interconnected so as to be cyclically actuated upon the repeated application of information and including means interconnecting the circuitry of each order to the circuitry of the next higher order to actuate the next higher order once during the cycle of each order, means for generating cyclic information to cycle said electronic circuitry of each order through a whole number of cycles, means to transmit said cyclic information to the electronic 45 circuitry of each order to cycle the circuitry thereof through a whole number of cycles and simultaneously to interrupt said interconnecting means, and means to intermittently interrupt the transmission of said cyclic information for a selected portion of said cycle corresponding to selected information to be accumulated, to 50 accumulate said selected information in said electronic register.
4. An electronic register as set forth in claim 3 in which said means to intermittently interrupt the transmission of said cyclic information includes digit selecting means, and means controlled by said digit selecting means to interrupt said transmission for a portion of said cycle equal to the complement of said selected digit.
5. A plural-ordered electronic decimal accumulator 60 comprising, a plurality of bi-stable electronic valve circuits interconnected within the respective orders to manifest by their relative stability statuses the modulo ten sum of impulses entered into each of the respective orders in parallel; means for entering a carry impulse 65 into the next higher order whenever the modulo ten sum of any given order exceeds nine; means for entering ten impulses into each order of the accumulator in each cycle of operation; means for suppressing the carry during each said cycle entering the ten impulses; entry control 70 means for registering the digital values of numbers to be entered in the respective orders of the accumulator; means under control of said entry means, and active during one cycle, for blocking the entry of that number of the continuously entered ten pulses which is equal to 75 the ten's complement of the digital values to be entered

11

into the respective orders; and means active during the cycle when said entry means is controlling, to activate the carry circuits; whereby every bi-stable circuit is operated during those cycles when the pulses are entered so as to obviate any deleterious effect of inactivity on 5 said valve circuits.

UNITED STATES PATENT OFFICE
CERTIFICATE OF CORRECTION

Patent No. 3,008,639

November 14, 1961

Arthur H. Dickinson

It is hereby certified that error appears in the above numbered patent requiring correction and that the said Letters Patent should read as corrected below.

Column 4, line 18, for "impulses" read -- impulse --; column 5, line 12, strike out "to", first occurrence; line 43, for "in" read -s is --; line 58, after "order", first occurrence, insert -- stands --; line 61, for "includes" read -- include --; column 6, line 10, for "tube" read -- tubes --; line 16, for "-4008-" read -- -0408- --. column 11, line 4, before "pulses" insert -- ten --.

Signed and sealed this 10th day of April 1962.
